EUGENE A. KUEN, OF CINCINNATI, OHIO, ASSIGNOR TO THE THOS. J. CORCORAN LAMP COMPANY, OF CINCINNATI, OHIO.

FASTENING FOR AUTOMOBILE-LAMP CLOSURES.

1,391,327.

Specification of Letters Patent. Patented Sept. 20, 1921.

Application filed July 23, 1920. Serial No. 398,476.

To all whom it may concern:

Be it known that I, EUGENE A. KUEN, a citizen of the United States, residing at Cincinnati, in the county of Hamilton and State of Ohio, have invented a new and useful Fastening for Automobile-Lamp Closures, of which the following is a full, clear, and exact description.

My invention has for an object to produce an improved fastening device for the doors or closures of automobile lamps, which will operate as a combined fastening and hinge for the closure.

A further object is to produce a fastening which will perform the function of fastening the lamp door or closure to the body while simultaneously preventing vibrations of the door relatively to the body and of the glass relatively to the rim of the closure, the body and the reflector.

A further object is to produce a combined closure fastening and hinge which will permit of complete detachment of the closure from the remaining parts of the lamp so that the interior of the lamp may be reached for purposes of lamp bulb renewal, reflector polishing, etc.

These and other objects are attained in the fastening described in the following specification and illustrated in the accompanying drawing in which:

Figure 1 is a transverse sectional view through an automobile lamp and illustrating my improved fastening in operative relation therewith.

Fig. 2 is an enlarged fragmental sectional view of a portion of the lamp illustrated in Fig. 1 and showing one fastening in operative position relatively to the body and closure.

Fig. 3 is a view similar to Fig. 2 but showing the fastener on the opposite side from that shown in Fig. 2, in detached or inoperative position relatively to the body and closure, the closure being shown in position somewhat removed from the body.

Fig. 4 is a perspective view of a pintle pin forming a detail of my invention.

Fig. 5 is a perspective view of two parts of one portion of my invention which co-operate directly with the pintle pin shown in Fig. 4.

My invention is shown applied to an automobile lamp of conventional type and having the usual body 5 containing therein the

usual reflector 6 which is closed by a glass 7 held within a closure rim 8 which fits over an annular rim 9 of the body. As is usual in such conventional constructions I have provided an annular packing ring 10 of asbestos or other suitable packing material. The usual prop brackets 11 and 12 are provided on the body 5 with the set screws 13 and 14 therein for securing the lamp to the props on the vehicle to which it is attached. Within the reflector is the lamp bulb 15 which is located within the adjustable connector 16 and which is operated by adjustment screw 17 accessible from the rear of the body.

The closure fastening device embodying my invention consists preferably of two portions, each portion consisting of two parts 18 and 19, the former being a relatively rigid part attached to the door or closure lining ring 20 by means of a fastening such as a rivet 21 and the part 19 being secured to the body by means of a fastening such as the bolt 22. Part 18 is provided with a looped end 23 which extends beyond the door rim and is provided for co-operation with the looped end 24 of part 19 of the fastening. Part 19, between its looped end 24 and its opposite end 25 through which fastening bolt 22 passes, is shaped to provide a yielding portion 26 which acts as spring so that the looped end may occupy either the dotted or full line positions shown in Fig. 3. The part 19 extends through an enlarged slot 27 in the body so that it has freedom of movement when being moved from one to the other of the positions shown in Fig. 3. The above referred to portions A and B of my improved fastening, are preferably located at diametrically opposite points on the lamp body and closure rim as shown in Fig. 1, so that the glass of the lamp closure will be held uniformly in tension against the packing ring 10 of the reflector 6, and it will be seen upon reference to Fig. 5 that the looped end of part 18 is made in two sections 23' and 23'', with the single section of loop 24 occupying the space between the sections of loop 23.

The pintle pin 28 is adapted to occupy both sections of the loop 23 and the single section of loop 24 when the fastening is in operative condition.

The operation of the parts 19 when they co-operate with parts 18 is to retain the closure glass 7 against the packing ring 10.

10 with a yielding pressure which is sufficient to prevent relative movement or vibration between the parts, the spring portions 26 of the members 19 operating to retain the parts in this yieldingly fastened relation to one another. In order to detach the members 18 and 19 of each portion of the fastening, it is but necessary to press member 19 toward the front of the lamp in 10 order to release the pintle pin 28 for removal. This operation may be performed on either side of the lamp so that the pintle pin of either one of the portions A and B may be removed in order that the closure 15 may be swung away from the lamp body upon that portion, the pintle pin of which has been left in position, thus permitting the other portion to operate as a hinge upon which the closure may be swung freely. Instead of this manner of operating the fastening the closure may be completely removed by removing both pintle pins in the 20 manner above described.

In replacing the closure it is located so 25 that the sections of loops 23 of members 18 are opposite loops 24 of members 19. The spring portions 26 are then pushed forward into position to bring loops 24 into coöperative position with loops 23 whereupon the pintle pins may be slipped within 30 the loops and the closure held in place.

It will thus be seen that by means of my 35 improved fastening the closure is held positively against rotative movement relatively to the body and reflector, and simultaneously therewith is held yieldingly toward the body with the glass in engagement with the packing ring of the reflector. This feature is 40 of advantage as compared with previous closure fastening devices in that although the door can not be displaced rotatively with relation to the body, the glass is protected against excessive strains and breakage by having the yielding pressure of spring members 19 exerted upon the closure to hold 45 the glass against packing ring 10.

Having thus described my invention what I claim is:

1. In combination with a lamp body and 50 closure therefor, a fastening for the closure consisting of a rigid member secured to one of said parts, a spring member secured to the other of said parts and normally ex-

tending away from the rigid member, and means adapted detachably to connect the 55 members when the spring member is flexed toward the rigid member and into engagement therewith.

2. A fastening for automobile lamp closures, comprising in combination with a 60 body and a closure therefor, a looped rigid member secured to the closure with the loop thereof extending beyond the closure, a looped spring member attached to the body with the loop thereof extending beyond the 65 body and away from the loop of the rigid member, and a pin removably mounted in and adapted to connect the loops when the spring member is flexed to bring the loop thereof into coöperative relation with the 70 loop of the rigid member.

3. In combination with a lamp body, and a closure for the body, a fastening comprising a rigid member secured to one of said parts, a spring member secured to another 75 of said parts away from the rigid member, and means adapted detachably to connect the members when the spring member is flexed to bring it under tension, whereby the closure will be held yieldingly toward the 80 body.

4. In combination with a body and closure therefor, a fastening for the closure consisting of a rigid member secured to one of 85 said parts, a spring member secured to the other of said parts and normally extending away from the rigid member, and means adapted detachably to connect the members when the spring member is flexed toward the 90 rigid member.

5. A fastening for automobile lamp closures, comprising in combination with a slotted body and a closure therefor, a looped rigid member secured to the closure, with the loop thereof extending beyond the 95 closure, a looped spring member attached at one end to the interior of the body, having the opposite end bent back over the attached end and extending beyond the body through the slot therein, said opposite end 100 having a loop adapted to register with the loop of the rigid member when the spring member is flexed, and a pin adapted removably to connect the loops when brought into registration.

EUGENE A. KUEN.
